[57] CLAIM

The ornamental design for an electronic calculator, as shown and described.

DESCRIPTION

FIG. 1 is a perspective view of an electronic calculator with the cover in open position showing our new design;

FIG. 2 is a front elevational view with the cover open of the electronic calculator;

FIG. 3 is a rear elevational view thereof with the cover open;

FIG. 4 is a front elevational view thereof with the cover closed;

FIG. 5 is a rear elevational view thereof with the cover closed;

FIG. 6 is a top plan view thereof with cover open;

FIG. 7 is a top plan view thereof with cover closed, the bottom plan view being a mirror image thereof;

FIG. 8 is a bottom plan view thereof with cover open;

FIG. 9 is a right side elevational view thereof with cover open, the left side elevational view being a mirror image thereof; and

FIG. 10 is a right side elevational view thereof with cover closed, the left side elevational view being a mirror image thereof.
